CHENEY KILBURN, OF PHILADELPHIA, PENNSYLVANIA, ASSIGNOR TO
KILBURN & GATES, OF SAME PLACE.

Design No. 4,423, dated October 18, 1870.

DESIGN FOR BOXES FOR BUREAUS.

The Schedule referred to in these Letters Patent and making part of the same.

I, CHENEY KILBURN, of Philadelphia, county of Philadelphia, State of Pennsylvania, have invented a Design for Boxes for the Tops of Bureaus, of which the following is a specification.

On reference to the accompanying drawing—

Figure 1 is a perspective view of a box made in accordance with my design;

Figure 2, a plan view of the same; and

Figures 3 and 4 plan views, illustrating modifications of the design.

The design consists in forming the front of the box upon any suitable curve, and the ends of the box upon straight lines tangential to that curve.

The box represented in figs. 1 and 2, for instance, has a semicircular front, *a*, and ends *b b*, parallel to each other, and formed on straight lines tangential to the curve *a*.

In figs. 3 and 4, the design is the same, the only difference being that the fronts of the boxes are formed upon oval or elliptical curves instead of being semi-circular.

I claim—

A box for the tops of bureaus, having its ends formed on straight lines, tangential to the curve upon which the front of the box is formed, all substantially as described, and as represented in and by the accompanying drawing.

In testimony whereof, I have signed my name to this specification in the presence of two subscribing witnesses.

CHENEY KILBURN.
